(57) **CLAIM**

The ornamental design for a bottle, as shown and described.

DESCRIPTION

FIG. 1 is a top perspective view of a first embodiment of a bottle according to our new and ornamental design;

FIG. 2 is a front elevation view thereof, the rear elevation view being identical thereto;

FIG. 3 is a side elevation view thereof, the opposite side elevation view being identical thereto;

FIG. 4 is a top plan view thereof;

FIG. 5 is a bottom plan view thereof;

FIG. 6 is a bottom perspective view thereof;

FIG. 7 is a top perspective view of a second embodiment of a bottle according to our new and ornamental design;

FIG. 8 is a front elevation view thereof, the rear elevation view being identical thereto;

FIG. 9 is a side elevation view thereof, the opposite side elevation view being identical thereto;

FIG. 10 is a top plan view thereof;

FIG. 11 is a bottom plan view thereof; and,

FIG. 12 is a bottom perspective view thereof.

The broken lines in FIGS. 1-12 illustrate portions of the bottle that form no part of the claimed design.

1 Claim, 10 Drawing Sheets
